UNITED STATES PATENT OFFICE.

FREDERICK J. HUMPHREY AND HUBERT R. HUMPHREY, OF KALAMAZOO, MICHIGAN.

GAS-LAMP.

1,244,051.

Specification of Letters Patent. Patented Oct. 23, 1917.

Application filed March 21, 1916. Serial No. 85,641.

To all whom it may concern:

Be it known that we, FREDERICK J. HUMPHREY and HUBERT R. HUMPHREY, citizens of the United States, residing at Kalamazoo, Michigan, have invented certain new and useful Improvements in Gas-Lamps, of which the following is a specification.

This invention relates to improvements in gas lamps.

10 The main objects of this invention are:

First, to provide in a gas lamp an improved pilot structure in which the pilot is disposed so as to be inclosed and protected by the mantle.

15 Second, to provide in a gas lamp an improved pilot structure having the above advantages in which the pilot and burner parts are adjustably supported so as to permit the easy assembling or renewal of the parts.

20 Further objects, and objects relating to details and economies of construction and operation will definitely appear from the detailed description to follow.

We accomplish the objects of our invention by the devices and means described in the following specification. The invention is clearly defined and pointed out in the claims.

25 A structure which is a preferred embodiment of our invention is clearly illustrated in the accompanying drawing, forming a part of this specification, in which:

30 Figure I is a vertical central section of a gas lamp embodying the features of our invention with certain parts shown in full lines.

35 Figure II is an enlarged inverted view of the burner and pilot, the mantle being sectioned, the pilot being shown in its operative position by full lines and in an inoperative position by dotted lines.

40 Figure III is a detail side elevation of the burner and pilot showing their relation to each other.

45 Figure IV is a horizontal section on a line corresponding to line 4—4 of Fig. I.

50 Figure V is an enlarged detail section on a line corresponding to line 5—5 of Fig. IV, showing details of the securing means for the burner adjusting member.

Figure VI is an enlarged detail section on a

line corresponding to line 6—6 of Fig. I, showing details of the pilot support.

Figure VII is an enlarged detail inverted view illustrating the movement of the pilot and the burner tip to bring them into proper operative relation, the parts being shown in full lines in an inoperative position and by dotted lines in operative position.

Figure VIII is a detail side elevation of a modified form of our improved pilot burner in which the pilot burner is formed integrally of the main burner tip.

Figure IX is a section through the burner of Fig. VIII, on a line corresponding to line 8—8 of Fig. VIII.

In the drawings, similar numerals of reference refer to similar parts throughout the several views, and the sectional views are taken looking in the direction of the little arrows at the ends of the section lines.

Referring to the drawing, the gas supply pipe coupling member 1 is provided with a valve designated generally by the numeral 75 2. As the valve forms no part of our present invention, we do not illustrate or describe the details herein. The coupling member 1 is provided with a nipple 3 at its lower end having the nozzle member 4 arranged to deliver downwardly threaded thereon. The lamp body is mounted on this coupling member and in the embodiment illustrated comprises a deflector plate 5 which constitutes a support member for the burner, as will appear as the description proceeds. Above this deflector plate is an air supply casing 6 mounted upon the tube or collar 7, which is, in turn, threaded upon the coupling member and provided with air inlet openings 8 surrounding the nozzle member 4. The burner mixing tube 9 projects into this tube 7 to receive the air and gas.

The air inlet casing 6 is provided with an air inlet opening 10 at its lower end. The deflector plate 5 has a portion 11 extending beyond the casing 6 and provided with flue discharge openings 12, there being, however, an imperforate portion below the opening 10 to constitute a guard or shield for protecting the opening 10 from the products of com-

bustion. This arrangement is substantially that shown in the application of Alfred H. Humphrey, filed August 9, 1915, Serial Number 44,626.

5 An upwardly flaring flue member 13 is mounted on the deflector plate to embrace the discharge openings 12 and constitutes a support for the globe 14. A skirt-like casting member 15 is also mounted on the deflector plate and constitutes a support for the shade or deflector 16. These parts are also substantially as shown in the said application for Letters Patent.

10 The burner tube 9, which is preferably of earthy material, has external threads 17 with which the collar-like adjusting member 18 is in threaded engagement. This adjusting member 17 has a flange 19 resting on the support member or deflector plate 5, thereby supporting the adjusting member for rotative movement. The adjusting member is secured in its adjusted positions by means of the clamping blocks 20, notched at 21 to engage the edges of the flange 19 and 15 clamped thereon by means of the screws 22 arranged through the plate from below so that the screws may be adjusted from below.

15 The burner 9 is preferably provided with an enlargement 23 at its lower end, internally threaded to receive the burner tip 24 which is also formed of earthy material. The burner tip has a shoulder 25 at its upper end and longitudinal ribs 26 terminating 20 in mantle supporting lugs 27, there being spaces between these lugs to permit the mantle supporting rings 28 being slipped longitudinally over the burner tip and then partially rotated to bring its lugs 29 into 25 engagement with the lugs on the burner tip. The mantle 30 is secured to the supporting ring in the customary way.

30 The pilot burner 31 is supported with its mouth in approximately the plane of the mouth of the burner tip. See Fig. III. The pilot burner tip is preferably beveled toward its outer side, as shown. With the tip thus supported, it is embraced or inclosed by the mantle. The pilot burner tube 32 is 35 angled and has threaded engagement with a coupling member 33 carried by the support member 5. Thus supported the pilot tube may be swung on its support to its operative position as shown with the pilot burner supported at the side of the main burner or swung away so as to permit the 40 convenient assembling or renewal of parts. The angle of the tube 32 is designed to swing under the enlargement at the lower end of 45 the burner tube 9. The shoulder 25 of the burner tip is provided with groove-like recesses 34 at one side of the ribs 26 to receive the pilot burner tube, permitting the

50 pilot burner being brought close to the side of the burner tip. As the threads of the burner tip are usually more or less irregular and to avoid the necessity of great care in assembling, the burner is made adjustable so that it may be adjusted to bring the parts in proper relation to permit the pilot burner 55 being swung close against the side of the main burner. It is found, in practice, that it is desirable to bring the pilot burner and main burner to approximately their proper position and then by rotating them in opposite directions, they are readily brought to place.

55 In the modified construction shown in Figs. VIII and IX, the pilot burner 35 is formed in the side of the main burner. 60 The mouth of the pilot burner is positioned in the same relation, however, as in the preferred construction. The pilot burner tube 35' is adapted to be engaged with a suitable opening at the upper end of the burner 35. 65 The advantage of rotating the burner in such a structure will also be appreciated.

70 The gas is supplied to the pilot through the supply tube 36 which is threaded into the coupling member 33 and connected to 75 the supply pipe coupling 1. A regulating valve 37 is provided for the pilot. With the pilot thus arranged, it is as stated inclosed by the mantle so that it is protected thereby and its flame is also covered so that it is 80 not ordinarily visible, when the lamp is extinguished. The pilot being thus protected, may be maintained with a low flame and at the same time the flame is so positioned that it immediately lights the gas, thus avoiding 85 explosions which would be likely to blow out the pilot or to fracture the mantle. It is also found that with the burner tube thus positioned, there is no deposit of carbon 90 therefrom on the chimney, and very satisfactory results are secured.

95 We have embodied our improvements in lamps of the general structure illustrated. Our improvements are, however, capable of embodiment in various other structures, but as we believe that the disclosure made will 100 enable those skilled in the art to which our invention relates to embody or adapt the same, as may be desired, we have not attempted to illustrate or describe such embodiments or modification.

105 Having thus described our invention what we claim as new and desire to secure by Letters Patent is:

110 1. In a gas lamp, the combination of a support member, a burner tube disposed through said support member and having an enlargement at its lower end internally threaded to receive a burner tip, a burner tip threaded into said burner tube and having 115 longitudinal ribs terminating in mantle

- supporting lugs, a collar-like adjusting member threaded upon said burner tube and provided with a flange resting on said support member whereby said adjusting member is supported for rotative adjustment, clamping blocks for said adjusting member, adjusting screws for said clamping blocks disposed through the said support member to permit their manipulation from below, 5 a pilot burner, an angled pilot burner tube mounted for rotative adjustment so that its burner end may be swung under the enlargement of said burner tube and at the side of one of said ribs of said burner tip and the pilot tip is supported close to the side of the main burner tip and with its mouth in approximately the plane of the mouth of the main burner tip, a mantle, and a mantle supporting ring engaged with said lugs supporting said mantle so that the pilot is embraced thereby. 10 15 20
2. In a gas lamp, the combination of a support member, a burner tube disposed through said support member and having an enlargement at its lower end internally threaded to receive a burner tip, a burner tip threaded into said burner tube and having longitudinal ribs terminating in mantle supporting lugs, an adjusting member on said burner tube supported for rotative adjustment on said support member, an angled pilot burner tube mounted for rotative adjustment so that its burner end may be swung under the enlargement of said burner tube and at the side of one of said ribs of said burner tip and the pilot tip is supported close to the side of the main burner tip and with its mouth in approximately the plane of the mouth of the main burner tip, a mantle, and a mantle supporting ring engaged with said lugs supporting said mantle so that the pilot is embraced thereby. 25 30 35 40
3. In a gas lamp, the combination of a support member, a burner tube disposed through said support member and having an enlargement at its lower end internally threaded to receive a burner tip, a burner tip threaded into said burner tube and having a shoulder at its upper end and longitudinal ribs terminating in mantle supporting lugs, said shoulder having recesses at the sides of said ribs, an adjusting member for said burner tube supported for rotative adjustment on said support member, a pilot burner, a pilot tube coupling member carried by said support member, a pilot gas supply tube connected to said coupling member, an angled pilot burner tube threaded into said coupling member for rotative adjustment so that its burner end may be swung under the enlargement of said burner tube and into one of the said recesses and at the side of one of said ribs 45 50 55 60
- of said burner tip and the pilot tip is supported close to the side of the main burner tip and with its mouth in approximately the plane of the mouth of the main burner tip, a mantle, and a mantle supporting ring engaged with said lugs supporting said mantle so that the pilot is embraced thereby. 65 70 75 80 85 90 95 100 105 110 115 120 125
4. In a gas lamp, the combination of a support member, a burner tube disposed through said support member and having an enlargement at its lower end internally threaded to receive a burner tip, a burner tip threaded into said burner tube and having a shoulder at its upper end and longitudinal ribs terminating in mantle supporting lugs, said shoulder having recesses at the sides of said ribs, an adjusting member for said burner tube supported for rotative adjustment on said support member, a pilot member, an angled pilot burner tube mounted for rotative adjustment so that its burner end may be swung under the enlargement of said burner tube and into one of the said recesses and at the side of one of said ribs of said burner tip and the pilot tip is supported close to the side of the main burner tip and with its mouth in approximately the plane of the mouth of the main burner tip, a mantle, and a mantle supporting ring engaged with said lugs supporting said mantle so that the pilot is embraced thereby. 80 85 90 95 100 105 110 115 120 125
5. In a gas lamp, the combination of a support member, a burner tube disposed through said support member, a burner tip carried by said burner tube and provided with mantle supporting lugs, an adjusting member on said burner tube provided with a flange resting on said support member whereby it is supported for rotative adjustment, means for securing said adjusting member in its adjusted positions, a pilot burner, an angled pilot burner tube mounted on said support member for rotative adjustment so that its burner end may be swung between said mantle supporting lugs and the pilot tip is supported at the side of the main burner tip and with its mouth in approximately the plane of the mouth of the main burner tip, a mantle, and a mantle supporting ring engaged with said lugs supporting said mantle so that the pilot is embraced thereby. 100 105 110 115 120 125
6. In a gas lamp, the combination of a support member, a burner tube disposed through said support member, a burner tip carried by said burner tube and provided with mantle supporting lugs, an adjusting member on said burner tube mounted on said support member for rotative adjustment, a pilot burner, a pilot burner tube mounted on said support member for adjustment so that its burner end may be adjusted between said mantle supporting lugs and the pilot tip is supported at the side of the main burner

tip and with its mouth in approximately the plane of the mouth of the main burner tip, a mantle, and a mantle supporting ring engaged with said lugs supporting said mantle 5 so that the pilot is embraced thereby.

7. In a gas lamp, the combination of an inverted burner, a pilot burner disposed at the side of said main burner with its mouth in approximately the plane of the mouth of 10 the main burner tip, the mouth of the pilot tip being beveled toward its outer side, and a mantle supported so that the pilot is embraced thereby.

Copies of this patent may be obtained for five cents each, by addressing the "Commissioner of Patents, Washington, D. C."

In witness whereof, we have hereunto set our hands in the presence of two witnesses. 15
